ERASER

John Glendinning, Jersey City, N. J., assignor to
Joseph Dixon Crucible Company, Jersey City,
N. J., a corporation of New Jersey

Application May 27, 1935, Serial No. 23,611

1 Claim. (Cl. 120—36)

The invention relates to an improvement in
erasers.

Of the various kinds of erasers employed in
the commercial world for cleaning or removing
from surfaces undesired material, such as dirt,
pencil and ink marks, typewritten and printed
letters, and the like, those in most common use
are of two kinds, one kind are adapted for removing
pencil marks and the other kind are erasers
particularly adapted for removing typewritten
and ink marks from the surface of paper. The
stenographer commonly employs both these kinds
of erasers in removing a misstruck letter or word
from the typewritten sheet. These erasers are
usually in disk form. The eraser especially
adapted for removing the ink typewritten letter
or word is usually composed of rubber with a
finely comminuted abrasive substance embedded
therein. When such erasers are used for remov-
ing the undesired letter or word from the paper
they leave the surface of the paper roughened
and with particles of the abrasive thereon, and then
an eraser composed chiefly of soft rubber is em-
ployed for removing the abrasive particles left
on the paper and for smoothing out the roughened
surface of the paper. As this operation has here-
tofore been performed it has required possession
of two separate erasers, one the ink eraser and
the other the soft or pencil eraser, the soft
eraser being also adapted for use in erasing pencil
marks or other stains from the paper. As is well
known, the two erasers frequently become sepa-
rated and one of them is temporarily lost, re-
quiring loss of time to locate it, thereby causing
some unnecessary inconvenience. Moreover,
even when the two erasers are kept in close
vicinity of each other the user after having em-
ployed the ink eraser must then put it down and
pick up the soft or pencil eraser, thus also entail-
ing an unnecessary waste of time and effort.

It is the object of the present invention to pro-
duce a device whereby the two erasers may be
held together in close vicinity of each other so
that neither will be lost without the other and
so that the operation of using them may be
facilitated without picking them up separately.
To this end the invention consists in the improved
eraser hereinafter described and claimed.

In the accompanying drawing illustrating the
preferred form of the invention, Fig. 1 is a side
elevation of an ink and a soft or pencil eraser held
together in close proximity according to the in-
vention and showing a brush attachment; and 5
Fig. 2 is a longitudinal section through the erasers
as indicated by the line 2—2 of Fig. 1.

The improved eraser device as illustrated in the
drawing comprises a conventional type of disk ink
eraser 5 and a conventional type of disk soft or 10
pencil eraser 6. According to the principle of
the invention these erasers are held in close
proximity by means of two pairs of arms 11 and
12 projecting from a yoke body 14. The ink
eraser 5 is pivotally held in the right hand ends 15
of the arms 11 by means of the hollow rivet 9,
and the soft or pencil eraser 6 is pivotally held in
the left hand ends of the arms 12 by the hollow
rivet 10. The outer ends of the rivets are swaged
over the adjacent parts of the arms in order to 20
hold the erasers firmly but rotatably on the arms.
The improved eraser device is provided with a
brush attachment 15 secured in the yoke body
14, for clearing away from the erased surface
any particles left after using either eraser. 25

The arrangement of the parts of the improved
eraser device is such as to conduce to the con-
venience of the user, especially the stenog-
rapher employed in typewriting. In using the
device, the eraser to be first used may be grasped 30
in any convenient manner, adapted to the idio-
syncrasies of the user, and the shift to the other
eraser is accomplished by simply turning the de-
vice in the hand holding it without putting the
device down. When either or both erasers have 35
been used, a short turn of the device in the hand
holding it brings the brush into play.

Having thus described the invention, what I
claim as new is:—

In a device of the class described, a yoke body 40
constructed and arranged for the support of a
brush element, and a pair of yoke arms diver-
gently extending from the yoke body and con-
structed and arranged for the support of adja-
cently positioned eraser elements. 45

JOHN GLENDINNING.
